(57) **CLAIM**

The ornamental design for a T-shaped raceway base, as shown and described.

DESCRIPTION

FIG. 1 is a perspective view, showing a segment of my new design for a raceway base of the present invention.

FIG. 2 is a right hand side view of the raceway base illustrated in FIG. 1, with the left hand side view being a mirror image thereof.

FIG. 3 is a front elevational view of a segment of the raceway base illustrated in FIGS. 1 and 2.

FIG. 4 is a rear elevational view of a segment of the raceway base illustrated in FIGS. 1-3; and,

FIG. 5 is a top plan view of a segment of the raceway base illustrated in FIGS. 1-4, with the bottom view being a mirror image thereof.
